UNITED STATES PATENT OFFICE.

PETER POOLEY, OF CHICAGO, ILLINOIS.

REVOLVING BROILER.

SPECIFICATION forming part of Letters Patent No. 694,889, dated March 4, 1902.

Application filed April 5, 1901. Serial No. 54,560. (No model.)

To all whom it may concern:

Be it known that I, PETER POOLEY, a citizen of the United States, residing at Chicago, in the county of Cook and State of Illinois, 5 have invented certain new and useful Improvements in Revolving Broilers, of which the following is a specification.

This invention relates to broilers for vegetables and meats; and its principal objects 10 are to provide a device for this purpose that will enable the article being broiled to be conveniently and readily revolved over the fire; that will economize the heating area by enabling a plurality of articles to be broiled in 15 close proximity and all rotated in unison by convenient means.

Other objects will be more fully pointed out hereinafter.

It consists in combining with a suitable fire- 20 box and its surrounding casing and appurte- nances suitable means for supporting the articles to be cooked and means for revolving all of the articles by turning one shaft and such other details and features as will be de- 25 scribed hereinafter and illustrated in the accompanying drawings, in which—

Figure 1 is a front elevation of a device embodying this invention. Fig. 2 is a plan view of the same. Fig. 3 is a side elevation. Fig. 30 4 is a detail showing hollow spindle. Fig. 5 is a detail of spindle with shank for turning- crank. Fig. 6 is a view showing holder. Fig. 7 is a view showing removable cover for fire-box. Fig. 8 is a view of handle for re- 35 moving fire-boxes. Fig. 9 is a sectional elevation taken at the right of shaft *k* in Fig. 2 and looking in the direction of said shaft.

A is a casing or body of a stove having the removable fire-boxes *a* *a'* mounted in the 40 rear portion thereof. Beneath the fire-boxes are slanting stationary slides *a²* *a³*, upon which the ashes fall and pass into a removable drawer *B*. At either side of the stove and immediately below the fire-boxes are 45 openings *c* *c'*, covered by slides *C* *C'*, which furnish easy access to start the fire and enables a pusher to be introduced to shove the ashes into the drawer in case they do not pass readily down. The front and side portions 50 of the casing form convenient storage-room for the fuel and cooking utensils and is rendered accessible by doors *D*.

A row of apertures *e* at the front of the cas-

ing furnishes means for the ingress of air and may be closed or regulated by a slide *E*. 55 The air thus admitted to the casing passes upward through holes *e²* in the top plate, thus furnishing a draft to carry away the heat and odor. Doors *a⁴* in the top plate may be turned up, as shown in Fig. 3, to protect the operator. A hood *G* over the stove may be connected with a chimney (not shown) by a pipe *g*. The lower part *g'* of the back plate of the hood *G* is hinged to allow access to the broiler from the rear. 65

The broiler apparatus comprises an upright plate *H*, in which are supported the spits *h* and gridiron-supports *h'*. These have shanks extending back through their bearings in the plate *H* to engage with intermeshing gear-wheels *i*. One of these shanks, as shown in Fig. 5, is still further extended to engage with a crank *j*, by means of which the whole system is turned. The plate *H* is hinged to the top plate of the stove to allow the spits and 70 gridirons to be turned up and away from the fire, as in Fig. 3. In case it is desired to operate the mechanism from the front a crank-shaft *k* is passed through bearing-posts *k'* and engages one of the gridiron-supports *h'*. 80

A hollow spit *h²* is adapted for use in case a large portion of meat or a fowl is to be broiled. The spit can be inserted in the article to be broiled and then slipped in position on one of the supports *h*. These spits are preferably 85 made of square tubing to engage the square supports *h* and are provided with sharpened points, as shown in Fig. 4. Gridirons or toasters *L*, (shown in Figs. 6 and 9,) provided with the usual wire cover, adapted to be held in a 90 closed position by a hook when the bread or meat has been inserted, are mounted on hollow square shafts adapted to engage the supports *h*. These gridirons may be slipped into position on the supports or removed therefrom while they are turning over the fire, and in order to do so readily they are provided with rotatable handles *l*, preferably of some non-conducting material, such as wood, fitting over shanks extending from the hollow 95 shafts. By arranging these as shown in Fig. 1 it is seen that the space over the fire is greatly economized, thereby reducing the amount of grate-surface needed, and consequently the fuel. 100 105

In operation the fire is started, with a cover

m (shown in Fig. 7) over the fire-box, and as soon as the fuel, which is preferably charcoal, is burning sufficiently the cover removed and the vegetables or meats placed 5 in position and turned by the crank, as shown. If the cooking is completed before the fire is out or it is desired to remove the fire, a pronged lifter *n*, Fig. 8, is adapted to engage with the end plates of the fire-boxes and furnish means 10 for removing them.

Various modifications may be made in the application of my invention, and I do not limit myself to the exact construction or detail shown; but

15 What I claim, and desire to secure by Letters Patent, is—

1. The combination of a casing provided with a draft-inlet in the front thereof and with outlets in its top plate, fire-boxes mounted in said casing, a revoluble broiler mounted over said fire-boxes provided with supports, and hollow broiler-spits adapted to engage with said supports. 20

2. The combination in a broiler of a casing, a fire-box mounted in said casing, revoluble 25 broilers mounted on a hinged plate proximate to said fire-box whereby said broilers may be turned away from the fire.

PETER POOLEY.
